UNITED STATES PATENT OFFICE.

WILLIAM GERALD HEMSWORTH AND THOMAS ANDREW HEMSWORTH, OF CHICAGO,
ILLINOIS.

FIXTURE ANCHORAGE.

Application filed June 10, 1927. Serial No. 197,978.

Our invention relates to improvements in devices for anchoring fixtures such as kitchen or bathroom fixtures to walls, and it consists in the combinations, constructions, and arrangements herein described and claimed.

Considerable difficulty has been experienced in mounting fixtures such as plumbing fixtures, kitchen sinks and lavatory basins, upon walls or partitions, due to the fact that the weight of these fixtures is apt to cause them to pull away from the wall. Attempts have been made to anchor devices of this kind, by embedding wood blocks 15 in the wall and to screw the holding devices, such as sink brackets, to this. The use of wood blocks requires considerable care or it will show on the finished plaster above the sink. The plaster will not readily trowel 20 over the block, since the blocks are not usually provided with keys.

An object of our invention is to provide an anchorage which forms a firm support for plumbing fixtures of the type mentioned 25 and which allows for a good smooth surface of plaster which will not crack or fall away from the anchor.

A further object is to provide an anchorage which may be used in connection with 30 ordinary wood screws or with toggle bolts.

A further object is to provide an anchorage of the type described which permits the screws or bolts to be put at varying positions without the necessity of shifting the 35 anchorage.

A further object is to provide an anchor construction which is all metal, but which provides for a good thread for a wood screw at any position selected.

40 A further object is to provide a wall anchorage structure which actually reinforces the wall at the point of suspension.

Other objects and advantages will appear in the following specification, and the novel 45 features of the invention will be particularly pointed out in the appended claims.

Our invention is illustrated in the accompanying drawings, forming part of this application, in which

50 Figure 1 is a front view of a wall portion showing the anchoring device, a portion of the wall being broken away,

Figure 2 is a vertical section along the line 2—2 of Figure 1,

Figure 3 is a vertical section through a 55 modified form of the device,

Figure 4 is an enlarged vertical section of a portion of the device shown in Figure 2, and

Figure 5 is a face view of a back plate. 60

In carrying out our invention, we make use of a metal plate 1 made in the form of a grille; that is to say, having openings 2 therethrough. In Figure 1, we have shown these openings as being square, although 65 they may be other shapes without departing from the spirit of the invention. This member 1 has at the back thereof a sheet 3 of galvanized iron and next to it a strip or layer of sheet lead 4. The back is formed 70 of a sheet of galvanized iron 5 whose edges are bent over the edges of the other sheets and of the body portion and around on the beveled front portion 1^a of the grille 1, as shown in Figures 1 and 2. The grille is provided with bolt openings for receiving staples 6 such as that shown in Figure 2. 75

In Figure 2, we have shown a section of a wall in which a metal lath 7 is secured on each side of studding 8, the studding in 80 this instance being angle iron. Bolts 6 extend through the plates 3, 4 and 5 and through a backing plate 9 adjacent to the metal lath 7, the nuts 10 of the bolts 6 being embedded in plaster 11. It will be under- 85

stood that this means of securing the grille in position is merely typical of many means that might be used. The grille itself is beveled at its edges as has been already explained and it is covered with plaster 12 so 90 that it is hidden from view. The openings in the front face of the grille permit plaster to enter so that the outer coating which covers the grille may be thin and yet may be readily troweled and when applied will 95 stay in position.

From the foregoing description of the various parts of the device, the operation thereof may be readily understood. In Figure 2, we have shown a portion of a bracket 100 13 having a socket 14 for receiving a portion of the device to be supported. The bracket may be secured to the anchor by ordinary wood screws such as that shown at 15 in Figures 2 and 4. In this instance, a hole is 105 punched through the plaster in the recesses of the grille and through the plates 3, 4 and 5 and the screw is placed in position and

turned as far as it will go. We have found that with the lead plate enclosed in between the galvanized iron plates, the screw will find a firm anchorage and will make its own threads so that it can be drawn up tightly.

Instead of using screws, we may use toggle bolts, such as that shown at 16 in Figure 3. In this instance, a hole is made through the plaster in the recess of the grille 10 and through the plates 3, 4 and 5 and the pivoted portion of the toggle bolt is inserted and the bolt is drawn tight against the bracket 13.

A fixture anchorage such as that described has numerous advantages. It can be made without defacing a wall, and in fact it reinforces the wall at the point where it is applied. It can be plastered over and the screws or bolts for holding the bracket may 20 be placed in different positions if one position is more desirable than another. This construction provides for a firm hold for the wood screw as well as for toggle bolts. It is readily installed at a comparatively 25 slight cost.

We claim:

1. A fixture anchorage, comprising a body portion having a plurality of openings therethrough, means for securing said body portion to a wall, and means carried by the rear face of the body portion for receiving

and holding a wood screw, said last-named means comprising a pair of sheet metal plates and a sheet of softer material disposed between said metal plates for spacing them 35 apart.

2. A fixture anchorage, comprising a body portion in the form of a grille, means for securing said body portion to a wall, a plurality of metal plates covering the openings 40 at the rear of the grille, the openings in front of said sheet metal plates being adapted to receive plaster, bracket holding means, and means for securing said bracket holding means to said plates, said last-named means being arranged to project 45 through said openings and through said metal plates.

3. A fixture anchorage, comprising a body portion in the form of a grille, means for securing said body portion to a wall, a plurality of metal plates covering the openings 50 at the rear of the grille, the openings in front of said metal plates being adapted to receive plaster, bracket holding means arranged to project through said openings and through said metal plates, and means for securing said bracket holding means to said plates.
